STARTING RELAY CIRCUIT FOR FLUORESCENT LAMPS

Robert F. Hays, Jr., Bloomfield, N. J., assignor to
 Westinghouse Electric & Manufacturing Company, East Pittsburgh, Pa., a corporation of Pennsylvania

Application October 10, 1940, Serial No. 360,529

6 Claims. (Cl. 176—124)

The present invention relates to gaseous discharge lamps and particularly to a time delay relay and circuit for starting and operating such lamps, especially those having at least one filamentary electrode adapted to be preheated to an electron-emitting temperature, such for example as what are now known to the art as fluorescent lamps.

Various circuit arrangements for the starting of fluorescent lamps are known to the art. One commonly used circuit utilizes a device provided with a pair of contacts, one of which is a bimetallic element surrounded by a heater. The contacts of the device are normally closed so as to complete a series heating circuit from a source of supply to the filamentary electrodes of the lamp. During the time that the filamentary electrodes of the lamp are being heated to electron-emissive temperature, the current is also flowing through the heater element so that the bimetallic element is heated at approximately the same time that the filamentary electrodes are heated to electron-emissive temperature, with the result that the contacts of the device open to interrupt the series heating circuit for the electrodes and initiate a discharge in the lamp.

Such an arrangement has the disadvantage that the discharge current for the lamp must flow through the heater element during entire operation of the lamp in order to maintain the bimetallic element heated and the contacts separated. Moreover, this type of thermal relay is not operable over a wide range of line voltage fluctuations and the heater element must necessarily be of a constant resistance and designed for one value of current to prevent its burning out.

Since the constant resistance of the heater is not the same as the filamentary electrodes of the lamp, inasmuch as the latter has a positive temperature coefficient of resistance, thereby causing a change of resistance with temperature, a thermal relay of this type cannot be designed for a wide variation of current so that operation thereof is delayed until the filamentary electrodes of the lamp reach optimum operating temperature. This is because a low current will not adequately heat the lamp electrodes to optimum temperature while at the same time the heater element is heated sufficiently to interrupt the heating circuit. On the other hand, if current is high and the lamp electrodes are heated to optimum temperature, then the heater element causes the heating circuit to remain closed

for too long a period, resulting in overheating of the lamp electrodes.

In order to eliminate the disadvantages of the above noted type of thermal relay, a glow switch is now in common use. Such type of glow switch is shown and described in Patent 2,200,443, issued March 14, 1940, to E. C. Dench, and assigned to the same assignee as the present invention. Such glow switch possesses the advantageous feature that it consumes no energy during operation of the lamp and is very positive in its operation over a long period of life.

Although such glow switch operates very satisfactorily for low wattage lamps, it possesses the disadvantage that it does not produce a sufficient time delay for heating the filamentary electrodes of higher wattage lamps, since upon operation its contacts do not remain closed sufficiently long to enable the electron-emitting temperature of the filamentary lamp electrode to reach its optimum temperature.

It is accordingly an object of the present invention to provide a time delay relay for starting a gaseous discharge lamp of the fluorescent type wherein the filamentary electrode of the lamp is preheated to optimum electron-emissive temperature prior to the initiation of a discharge in the lamp.

Another object of the present invention is the provision of a starting circuit for a gaseous discharge lamp of the fluorescent type having a filamentary electrode and wherein a starting relay is employed which has a sufficient time delay to enable the filamentary electrode of the lamp to be preheated to an optimum electron-emitting temperature.

Another object of the present invention is the provision of a starting circuit for a gaseous discharge lamp of the fluorescent type having a filamentary electrode and wherein a starting relay is employed which has a sufficient time delay to enable the filamentary electrode of the lamp to be preheated to an optimum electron-emitting temperature, regardless of wide variations in current range.

Another object of the present invention is the provision of a time delay relay particularly adaptable for the starting of a gaseous discharge lamp having at least one filamentary electrode adapted to be preheated to an optimum electron-emitting temperature wherein the relay can be readily inserted in a socket and connected so as to complete a series heating circuit for the filamentary electrode, and is operable with a sufficient time delay so as to preheat the fla-

mentary electrode to optimum electron-emitting temperature over a wide current range.

Still further objects of the present invention will become obvious to those skilled in the art by reference to the accompanying drawing wherein:

Fig. 1 is a diagrammatic illustration of an electrical circuit for starting and operating a gaseous electric discharge lamp and employing a time delay relay in accordance with the present invention.

Fig. 2 is an elevational view of the elements of the time delay relay itself with some of the elements being shown diagrammatically.

Fig. 3 is an elevational view of a modification of one of the elements of the time delay relay of the present invention.

Fig. 4 is a sectional view taken on the line IV—IV of Fig. 3.

Fig. 5 is still another modification of one of the elements of the time delay relay of the present invention.

Fig. 6 is a sectional view taken on the line VI—VI of Fig. 5.

Referring now to the drawing in detail, a gaseous electric discharge device, such as a fluorescent lamp 5, is shown in Fig. 1 which is provided with oppositely disposed filamentary electrodes 6 and 7 of a refractory metal, such as tungsten or the like, in the form of a coiled coil coated with an electron-emissive material, such as an oxide of barium, strontium or the like, to provide a copious flow of electrons when heated to an optimum temperature.

After evacuation the lamp is filled with a rare gas at a few millimeters pressure to facilitate starting, to which is added a few drops of mercury. As shown in Fig. 1, one terminal of the electrode 6 is connected by a conductor 8 through an impedance element in the form of an inductance 9 to one side of the source of supply of the customary domestic potential of 115-230 volts. Likewise, one terminal of the electrode 7 is connected by a conductor 10 and switch 12 to the opposite side of the domestic source of supply. The remaining terminal of each electrode is connected together through the medium of a time delay relay so that upon operation thereof the electrodes 6 and 7 of the lamp 5 are in series with each other and the source of supply, whereby the electrodes are preheated to an optimum electron-emitting temperature.

When the temperature of the electrodes reaches this optimum temperature, the time delay relay operates to interrupt the series heating circuit for the filamentary electrodes, thus causing a discharge therebetween with the time delay relay being shunted from the circuit and consuming no energy during operation of the lamp.

The system thus far described differs very little from the circuits of the prior art above noted, with the exception of the construction and operation of the time delay relay device 13. The auxiliary discharge device 13 as shown in Fig. 1 comprises a casing 14 provided with a pair of terminals 15 readily engageable in an appropriate socket so as to connect the time delay relay 13 in a series heating circuit as shown.

By reference more particularly to Fig. 2, the various elements contained within the casing 14 comprise a glow switch 16 and what will be hereinafter termed a thermal device 17 together with a radio frequency suppressing capacitor 18. The glow switch 16 is of the type shown and de-

scribed in the above-mentioned Patent 2,200,443 and is provided with a pair of electrodes 19 and 20, the latter of which is a bimetallic element provided with an electron-emissive material 22. An ionizable medium, such as neon, argon or helium or a mixture thereof, at a pressure of approximately 75 to 100 millimeters, is disposed in the switch, and upon the application of a potential to the electrodes, the gaseous filling is ionized, causing a glow discharge between the electrodes.

Due to this relatively high pressure a substantial current flows during the discharge which heats the bimetallic electrode 20 with the result that it very rapidly deflects into engagement with the other electrode 19 to extinguish the discharge and at the same time complete the series circuit for the electrodes of the lamp. After the bimetallic electrode 20 cools, it returns to its normal spaced relation relative to the electrode 19. As previously mentioned, this glow switch operates very satisfactorily for lamps ranging in wattage up to approximately 30 watts since the time of engagement of the electrodes is adequate to heat the filamentary electrodes of the lamp to optimum electron-emitting temperature. However, filamentary electrodes of higher wattage lamps require more time for pre-heating; and the damage caused by inadequate electrode heating is much greater in such higher wattage lamps than in the case of smaller lamps because of resulting electrode sputtering.

Thus it is essential in higher wattage lamps to allow the filamentary electrodes to be heated to an optimum temperature entirely independent of line voltage fluctuations or circuit characteristics in order that a discharge be initiated in the lamp following initial operation of the relay. To insure heating of the filamentary electrodes 6 and 7 to the optimum electron-emitting temperature independent of line voltage fluctuations and circuit characteristics, the time delay relay of the present invention includes the thermal device 17 which comprises an envelope provided with a gaseous medium such as helium at a pressure substantially lower than the pressure of the medium within the glow switch 16 of about 5 millimeters. This thermal device is provided with a pair of normally closed contacts 23 and 24, the latter of which is a bimetallic element. In addition, a resistance heater element in the form of a tungsten filament 25 is disposed in the thermal device adjacent the electrode 24, which resistance heater element has substantially the same thermal and electrical characteristics as that of the filamentary electrodes 6 and 7.

As will be noted from Fig. 2, the thermal device 17 is in electrical series with the glow switch 16 through a connection 26, with the entire time delay relay 13 being connected in the circuit so as to form a series heating circuit for the electrodes, as previously mentioned. In addition, the radio frequency suppressing capacitor 18 is connected in parallel with the electrodes of the glow switch 16 so as to absorb radiations of radio frequency to prevent interference with radio reception.

Upon closure of the switch 12 the voltage of the source of supply is impressed upon the electrodes 19 and 20, of the glow switch 16 which extends from the source of supply through the inductance 9, conductor 8, filamentary electrode 6 of the lamp 5, and through the terminal 15 to the electrode 19, and also through the switch 12, conductor 10, filamentary electrode 7, relay

terminal 15, normally closed thermal relay contacts 24 and 23, through resistance heater element 25 and connection 26 to the electrode 20.

This voltage is sufficient to cause ionization of the ionizable medium within the glow switch 16 with an attendant discharge between the electrodes 19 and 20. The electrode 20 is accordingly heated very rapidly and, as above mentioned, is deflected into engagement with the electrode 19. The series heating circuit for the filamentary electrodes 6 and 7 of the lamp 5 is accordingly completed. When the electrodes 19 and 20 engage each other, the glow discharge is thereby extinguished. The electrode 20 is so designed that the I^2R effect is such that the flow of current in the heating circuit for filamentary electrodes 6 and 7 is sufficient to maintain the electrode 20 of the glow switch in a heated condition so that the electrodes 19 and 20 are maintained in engagement with each other.

Closure of the heating circuit not only heats the filamentary electrodes 6 and 7, but since the resistance heater element 25 is likewise in series in said circuit and has the same thermal and electrical characteristics as the filamentary electrodes, it is likewise simultaneously heated. Consequently, by the time the filamentary electrodes 6 and 7 of the lamp 5 have reached optimum electron-emitting temperature, the resistance heating element 25 will likewise be heated to a temperature sufficient to cause the bimetallic contact 24 of the thermal device 17 to be heated, causing deflection thereof and separation from the contact 23.

This interrupts the heating circuit for the filamentary electrodes 6 and 7 and since the gas pressure in the thermal device 17 is very low, no arcing between the contacts 23 and 24 occurs, and such low gas pressure at the same time permits a high transient voltage surge from the inductance 9 which initiates a discharge between the electrodes 6 and 7 of the lamp 5. During operation of the lamp 5 the time delay relay 13 consumes no energy from the source of supply, despite the fact that the contacts 23 and 24 again assume their normally closed position upon cooling of the bimetallic contact 24 and resistance heater element 25, and that the electrodes 19 and 20 likewise assume their normally open position upon cooling of the bimetallic electrode 20, because the voltage impressed across the electrodes 19 and 20 during operation of the lamp 5 is insufficient to again initiate a discharge in the glow switch 16.

The time delay relay of the present invention eliminates an inherent defect existent in glow switches of the type hereinbefore mentioned. For example, when a glow switch alone such as 16 is used for starting a lamp, the glow switch and the condenser customarily connected in parallel with it for reducing radio interference are subjected to a high voltage surge when the switch contacts open. This high voltage surge, while serving to start the discharge in the fluorescent lamp, also drives gases out of the electrodes of the switch and the envelope walls of the glow switch. Such occluded gases contaminate the gas with which the glow switch is filled and cause clean-up of the original filling gas, so that the electrical characteristics of the glow switch are altered and the switch may be inoperative. Since the condenser must withstand the high voltage surge, it must necessarily be of a high quality and therefore expensive.

In the present invention, as above noted, the

glow switch only closes the circuit and does not interrupt it, with the result that the glow switch contacts and the radio frequency suppressing condenser are not subjected to the high voltage surges, so that the defects above mentioned are eliminated. Moreover, since the glow switch does not interrupt the flow of current, arcing of the glow switch contacts is eliminated and the longevity thereof is considerably improved.

A further important feature of the present invention resides in the fact that the thermal device 17 forming a part of the time delay relay operates as a protective device in the event the lamp 5 fails for any reason to start. For example, when the bimetallic contact 24 is heated, it separates to permit a high voltage surge, as above noted. Since this also interrupts the heating circuit, the heater 25 as well as the electrodes 6 and 7 of the lamp 5 will naturally cool. Upon reclosure of contacts 23 and 24 if the lamp 5 does not start, the heating circuit is again closed and the contacts operate through the same cycle. However, once the bimetallic contact 24 is heated, it will remain in the open condition the greater portion of the time, with closure thereof of approximating only 10% of the time, thus preventing excessive heating of the auxiliary circuit elements such as the impedance element 9.

In Figs. 3 and 4 a modification of the thermal device 17 is shown which differs from that of Fig. 2 in that in lieu of a resistance heater element in the form of a tungsten filament 25, a high resistance element 27 of silicon, carbon or the like, is carried by the bimetallic contact 24 which engages the contact 23. Again, the operation of the thermal device is identical to that previously described in connection with the modification shown in Fig. 2, and the thermal characteristics of the high resistance element 27 are designed so as to correspond to that of the filamentary electrodes 6 and 7 of the lamp to insure opening of the contacts 23 and 24 only after the filamentary electrodes 6 and 7 have reached optimum electron-emitting temperature.

The same equally applies with respect to the modification of the thermal device shown in Figs. 5 and 6 wherein the bimetallic contact 24 itself is so designed that its resistance is such that the flow of current therethrough heats the same to a temperature sufficient to cause separation of the contacts only after the filamentary electrodes 6 and 7 reach their optimum electron-emitting temperature.

It thus becomes obvious to those skilled in the art that a time delay relay device is herein provided which is particularly adaptable to the starting of fluorescent lamps. Moreover, such time delay relay is so designed that its operation is entirely independent of line voltage fluctuations or circuit characteristics because the same current which heats the filamentary electrodes of the lamp also heats one of the elements of the time delay relay, which insures adequate preheating of the filamentary electrodes to their optimum electron-emitting temperature prior to operation of the circuit opening element of the time delay switch. By the provision of a time delay relay insuring preheating of the filamentary lamp electrodes to optimum electron-emitting temperature, the initiation of a discharge between the electrodes invariably occurs without sputtering of the lamp electrodes, following initial operation of the time delay relay, with attendant high voltage surge which eliminates any necessity for repetition of its cycle of operation.

Although several embodiments of the present invention have been shown and described, it is to be understood that other modifications thereof may be made without departing from the spirit and scope of the appended claims.

I claim:

1. A time delay relay for starting a gaseous electric discharge lamp having at least one filamentary electrode adapted to be preheated to an optimum electron-emitting temperature comprising a glow switch and a thermal device adapted to be connected in electrical series relation with each other and in a heating circuit for the electrode of said lamp, said glow switch being operable to close the heating circuit for said electrode upon the application of a potential thereto, and said thermal device having a pair of contacts normally closed prior to initiation of a discharge in said lamp and operable to open following operation of said glow switch and provided with a heater element connected in series with said glow switch and the normally closed contacts of said thermal device and having preselected characteristics for heating said contacts simultaneously with the heating of said electrode to optimum electron-emitting temperature to cause opening of said contacts and interruption of the heating circuit for said electrode and said heater element with attendant initiation of a discharge in said lamp.

2. A time delay relay for starting a gaseous electric discharge lamp having at least one filamentary electrode adapted to be preheated to an optimum electron-emitting temperature comprising a casing provided with terminals for connecting said relay in a heating circuit for the electrode of said lamp, a glow switch in said casing adapted to close the heating circuit for said electrode upon the application of a potential thereto, and a thermal device in said casing having a pair of contacts normally closed prior to initiation of a discharge in said lamp and included in the heating circuit for said electrode upon operation of said glow switch and provided with a heater element connected in series with said glow switch and the normally closed contacts of said thermal device and having preselected characteristics for heating said contacts simultaneously with the heating of said electrode to optimum electron-emitting temperature to cause opening of said contacts and interruption of the heating circuit for said electrode and said heater element with attendant initiation of a discharge in said lamp.

3. A time delay relay for starting a gaseous electric discharge lamp having at least one filamentary electrode adapted to be preheated to an optimum electron-emitting temperature comprising a glow switch operable to close a heating circuit for the filamentary electrode of said lamp and provided with a pair of normally spaced electrodes therein, an ionizable medium in said tube at a pressure sufficiently high to cause rapid closure of the spaced electrodes upon the application of a potential thereto, and one of said electrodes being a bimetallic element initially heated by the discharge to cause engagement of

said electrodes and extinguishment of said discharge and adapted to be thereafter heated by the flow of current therethrough to maintain said electrodes in engagement to complete the heating circuit for said filamentary electrode; and a thermal device having a pair of contacts normally closed prior to initiation of a discharge in said lamp, at least one of which is a bimetallic element having preselected characteristics and provided with a heater element connected in series with said glow switch and the normally closed contacts of said thermal device and for heating said bimetallic element simultaneously with the heating of said filamentary electrode to optimum electron emissivity to cause opening of said contacts and interruption of the heating circuit for said electrode and said heater element, and a gaseous medium in said thermal device at a pressure substantially less than that in said glow switch to enable the passage of a high transient voltage for initiating a discharge in said lamp at the instant of interruption of the heating circuit by opening of the contacts of said thermal device.

4. A starting relay for discharge lamps of the fluorescent type comprising a casing provided with contacts engageable with a socket, a glow switch disposed in said casing and having normally separated contacts adapted to close upon the occurrence of the glow discharge in said glow switch, and a thermal switch disposed in said casing having a heat-responsive element and provided with an electric heater operable by closure of the contacts of said glow switch to cause heating of said heat-responsive element with attendant operation thereof after the lapse of a predetermined period of time to interrupt current flow through said glow switch.

5. A starting relay for completing a circuit to a discharge lamp of the fluorescent type comprising a casing, a glow switch disposed in said casing and having normally separated contacts adapted to close the circuit to said lamp upon the occurrence of a glow discharge in said glow switch, and a thermal switch having a heat-responsive element and an electric heater operatively included in said circuit upon closure of the contacts of said glow switch and said heater being operable to heat said heat-responsive element and cause the latter to interrupt the circuit to said lamp after the lapse of a predetermined period of time.

6. A starting relay for completing a circuit to a discharge lamp of the fluorescent type comprising a casing, a glow switch disposed in said casing and having normally separated contacts adapted to close the circuit to said lamp upon the occurrence of a glow discharge in said glow switch, and a thermal switch having a heat-responsive element and an electric heater operatively included in said circuit upon closure of the contacts of said glow switch and said heater being operable to heat said heat-responsive element with attendant operation thereof after the lapse of a predetermined period of time to interrupt current flow through said glow switch.
